ROTARY TERRACER

Orrin K. Howe, Memphis, Tex.

Application August 14, 1940, Serial No. 352,615

11 Claims. (Cl. 37—114)

This invention relates to rotary terracers and more particularly to such a machine for use in the construction of broad-base terraces but without limitation thereto as a machine embodying the present invention is also ideally adaptable for road grading and other uses.

The invention has for its prime object to improve generally upon terracing and grading machines of the rotary type so as to increase the efficiency of such machines and secure a better control in the operation of the machine and a more even and advantageous distribution of the carried soil.

Another object is to simplify and lighten the structure without detracting from the strength and durability thereof so as to minimize the cost of construction and maintenance of the machine and, at the same time, provide for a substantial increase in the distance the material is carried on a traveling part of the machine rather than being moved on the machine slidably with frictional resistance.

A further object is to minimize the straight forward draft resistance of the machine and also the lateral deflection and shifting of the machine in its forward travel.

A still further object is to secure an equal balance of the machine and to operate the machine with no excess height of lift or pulverizing of the dirt.

With the foregoing and other objects and advantages to be attained, as will hereinafter more fully appear, the invention consists in the novel general structure and in the several parts and combinations and arrangements of parts thereof, as hereinafter described and set forth with particularity in the appended claims, reference being had to the accompanying drawings, in which,

Figure 1 is a top plan view of one form of the machine;

Figure 2 is a section taken on or about the line 2—2 of Figure 1;

Figure 3 is a section taken on or about the transverse line 3—3 of Figure 1;

Figure 4 is a fragmentary section taken on or about the diagonal line 4—4 of Figure 1;

Figure 5 is a top plan view of a modified form of the machine;

Figure 6 is a section taken on or about the transverse line 6—6 of Figure 5;

Figure 7 is a section taken on or about the longitudinal line 7—7 of Figure 5; and

Figure 8 is a fragmentary plan view illustrating a modification of the scraper element where-

in an endless belt is substituted for the rotary drum illustrated in Figures 5, 6 and 7.

Referring now to the drawings in detail and more particularly to Figures 1 to 4, inclusive, the numeral 1 designates the main rotary disklike table element or soil carrier of the machine, the same being of an annular form, that is to say, it has a central circular opening 2 whereby its soil carrying portion is annular or ringlike in form. This rotary table or soil carrier 1 is rotatably mounted on and within an open frame the longitudinal portion of which is substantially rectangular and a part of the transverse portion of the frame is substantially rectangular, the rest of the transverse portion of the frame being of slightly different formation and open at one side thereof. That is to say, the longitudinal portion of the frame comprises two U-shaped sections 3 and 4, respectively, with their respective leg members 3^a, 3^b, and 4^a, 4^b aligned and riveted at their inner ends, as at 3^c and 4^c to upper and lower circular plates 5 and 6, respectively, while the transverse portion of the frame comprises an upper bar 7 which is riveted, as at 7^a to the upper plate 5, to which plate and diametrically opposite and in lengthwise alignment with the bar 7, the leg member 8^a of a substantially U-shaped section 8 is attached, as at 8^b, said section 8 having a portion of its opposite leg parallel with the leg 8^a, as at 9, the remainder of the leg converging toward the lower plate 6, as at 9^a, and being attached to the plate, as at 9^b, with a wedge-shaped filler 10 between its end portion and the plate (see Figure 3).

The aforesaid frame structure including the aligned longitudinal sections 3 and 4 and the transverse bar 7 and section 8, connected as they are to the upper and lower plates 5 and 6, is of ample rigidity to support and carry the rotary table or soil carrier 1 thereon and the rigidity and stability being further enhanced by the peculiar provision in the mounting of said element 1 on the frame as will now be described.

Secured axially in the upper and lower plates 5 and 6 of the main frame of the machine is a strut member 11 which serves as a support on which the table or soil carrier 1 is rotatably mounted, said strut member 11 being secured at its opposite end portions in bores provided therefor in the central portions of the plates 5 and 6, which portions are reinforced on the outer faces of the plates by bosses 12, the fastening of the strut member 11 in place being by any obvious means such as cross-pins or nut members applied to the outer end portions of the member 11 or

even by a welding process or the equivalent. The rotary table or soil carrier 1 is provided at the center of its opening 2 with a hub member 13 which is connected to the inner peripheral portion of said element 1 by a series of radial members or spokes 14, said hub member having a boss or bearing protuberance 15 on its underside which rests and rotates upon the adjacent top face portion of the lower plate 6 of the main frame of the machine.

The main frame of the machine is tilted both longitudinally and transversely, that is to say, it is provided with a pair of supporting ground wheels 16 at the rear thereof which maintain the rear portion of the frame at a considerable distance above the ground, and a single ground wheel 17 of much smaller diameter than the rear wheels 16 at the front end of the longitudinal frame section 3, said wheel 17 supporting the adjacent end portion of the frame close to the ground. The wheel 17 tracks in close relation to the longitudinal axis of the machine while the two rear wheels 16 are disposed equi-distant on opposite sides of the longitudinal axis of the machine. The front wheel 17 is mounted conventionally on a lateral stub-bearing-extension 18 located at the lower corner of the forward frame section 3 (see Figures 1 and 2). The pair of rear ground wheels 16 have a trailing casterlike mounting on the main body frame of the machine, the same including downwardly and rearwardly curved forks 19 whose shank portions 20 are respectively swiveled in vertically bored bearing portions 21 provided at the rear ends of a pair of longitudinal auxiliary frame members 22. The frame members 22 are attached at their forward ends, one to the transverse frame bar 7, as at 22^a, and the other likewise to the upper leg 8^a of the transverse frame section 8, as at 22^b, the frame member 22 which is located to the left of the longitudinal axis of the machine being, of course, in a lower plane than the other frame member 22 at the opposite side of the axis, this being due to the aforesaid transverse inclination of the main frame of the machine, and because of which the bearing portion 21 at the end of the frame member 22 to the right of the longitudinal axis of the machine is, obviously, either located lower than the corresponding bearing portion on the opposite frame member 22 or accordingly elongated and extended downwardly if the two forks 19 are identical in size and shape, or the fork 19 which carries the wheel to the right of the longitudinal axis of the machine may be extended upwardly to where the shank portion 20 is provided thereon.

The main body frame of the machine, in the construction and arrangement illustrated in Figures 1 to 4, inclusive, further includes a pair of diagonal, substantially U-shaped sections 23 which diverge from the upper and lower central plates 5 and 6, the upper legs 23^a and lower legs 23^b of said sections 23 being secured at their inner ends to the upper and lower plates 5 and 6, respectively, as at 23^c, in the same manner as the hereinbefore described other frame members are attached to said plates. The rear end portions of the diagonal frame sections 23 are cross-connected by a transverse bar 24 to which the longitudinal frame members 22 are fastened, as at 25, and there is a further bracing 26 which extends diagonally between the rear end of the longitudinal frame section 4 and the ends of the respective diagonal frame sections 23 (see Figure 1). The longitudinal frame members 22 are

5 also secured to the diagonal braces 26, as at 27. Said longitudinal frame members 22 are also preferably secured to the diagonal frame sections 23, as at 25^a, where they cross the upper legs of said sections 23 (see Figures 1 and 4).

Extending laterally and perpendicularly to the left from the front end of the forward longitudinal frame section 3, is a frame bar 28, which, preferably as shown in Figure 2, is of round cross section. Secured at its forward end to the outer end of said bar 28 is a rearwardly extending longitudinal side frame bar 29, preferably of rectangular cross section, as shown more clearly in Figure 3, said longitudinal bar 29 carrying, as 10 shown, an oblique ground scraper 30 comprising a flat plate which is secured at its upper forward portion to the bar 29, as at 31, the scraper being attached at its upper rear end portion to the bar 29 by a cross brace 32. The lower rear corner 15 portion of the scraper 30 is cut away, as at 33, to clear and accommodate the marginal portion of the table or soil carrier 1 as it travels thereunder close to the ground (see Figure 3). The longitudinal side frame bar 29, just to the rear of 20 the cross brace 32 which connects the scraper 33 to the bar, is connected to the outer end portion of the transverse main frame bar 7 by a bracket member 34. Preferably, the longitudinal side frame bar 29 is extended rearwardly from the 25 bracket 34 and connected at its end to the end of the adjacent diagonal frame section 23 by a cross brace 35, which latter is preferably aligned with the cross brace 24 connecting the ends of the two 30 diagonal frame sections 23 (see Figure 1).

35 Normally, the annular table or soil carrier 1 is supported on a ground wheel 36 at a point substantially diametrically opposite the lowermost portion of its periphery which travels close to the ground and under the cut away portion 33 of the 40 scraper element 30 (see Figure 3), the wheel 36, which is preferably rubber-tired, being set at an inclination so that it is substantially perpendicular to the underside of the marginal portion of the table or soil carrying element 1 which 45 rests thereon and by the contact thus made between said element 1 and the wheel 36, the latter, in its rolling travel on the ground, imparts rotation to the element. The inclined set of the wheel 36 and its perpendicular relation to the 50 marginal portion of the table or soil carrying element 1 is maintained because of it being journaled on the lower inclined leg portion 9 of the transverse frame section 8. In this connection, it is noted that the hub portion 37 of the wheel 36 55 is shiftable longitudinally on said leg portion 9 of the frame section 8 by and under the control of a hand lever 38 which is pivotally mounted, as at 39, on a sector bracket 40, the end portions of which latter are secured to the intermediate base portion of the frame section 8, as at 41, and the lower end portion of the lever being pivotally attached, as at 42, to a link 43, which, in turn, is swivelly attached, as at 44, to the outer end of the hub 37 of the wheel 36. 60 The hand lever 38 is provided with a conventional latch element 45 which is engageable in the toothed portion of the sector whereby the lever is held in different positions to which it is moved, and said latch element being under the control of a conventional releasing lever 46 located adjacent the grasping portion of the hand lever and having the usual rod connection 47 with the latch element 45. By manipulation of the hand lever 38 the ground wheel 36 is shifted on the leg portion 9 of the frame section 8 in the direction to 65

operate under the table or soil carrying element 1 or in the opposite direction from under the element 1, at the will of the operator.

The annular table or soil carrying element 1 is supported on several antifriction rollers 48 which are provided on the respective frame members 3^b, 4^b and 23^b so that said element 1 is more easily rotated under the driving action of the ground wheel 36, said rollers 48, other than that located on the frame member 3^b, being located in the region where the preponderance of the load is carried on said element 1. At the forward end of the machine is provided, the chain, as shown, including convergent links 49 and 50 which are respectively attached one to the forward end portion of the longitudinal side bar 29, as at 51, and the other to the front end of the forward longitudinal frame section 3, as at 52, said links 49 and 50 being joined at their meeting ends by a ring member 53 for effecting attachment to a draft medium such as a tractor or a horse-drawn or tractor-drawn or propelled plow, the links 49 and 50 being proportioned in length and the ring member 53 located so that the machine of the present invention is drawn forward in use in a straight line without undue tendency to shift laterally from the line of draft.

Obviously, instead of providing the oblique scraper element 30, as shown in the drawings, a V-shaped drag disk or a plowshare with a moldboard attached thereto may be provided on the machine of the present invention or the machine may be hitched to a grader provided with either an oblique or V-shaped digger or drag element or a conventional moldboard plow which travels in alignment ahead of the scraper element 30 or other suitable elements substituted therefor on the machine of the present invention, which element 30 or its substitute, deflects the soil loosened ahead of it onto the rotating table or soil carrier element 1, whence the material thereon is discharged by means to be now described.

In the structure illustrated in Figures 1 to 4, inclusive, the central opening 2 of the annular table or soil carrying element 1 is surrounded by an upstanding annular flange 54 which, as shown, is provided with an inturned flange 55 at its lower edge, said flange resting upon the outer end portions of the radial members or spokes 14 of the table or soil carrying element 1 and being fastened to said element 1 by the same rivets or fastening means which secure the radial members or spokes 14 to said element 1. This annular flange 55 constitutes a guard to prevent the material on the table or soil carrying element 1 from moving therefrom through the central opening 2. Cooperating with the annular flange or guard 55 is an arcuate deflecting scraper 56 which, as shown, is hingedly mounted, as at 57, on the intermediate base portion of the U-shaped transverse frame section 8 (see Figures 1 and 3), said scraper element 56 extending over the top face of the table or soil carrying element 1 with its lower edge portion in close scraping contiguity thereto and the otherwise free end portion of said element 56 being in sliding contact with the circumferential facing of said annular flange or guard element 54. By this provision, when the table or soil carrying element 1 rotates in the direction indicated by the arcuate arrows in Figure 1, during the forward travel of the machine, the loosened soil which is deflected by the scraper element 30 onto the adjacent lowermost portion of said element 1 is carried by the element to the rear and to the right of the central guard

flange 54 whence it is deflected from the machine as it is brought into contact with the deflecting scraper element 56. To prevent the material from being forced rearwardly off the table or soil carrying element 1 within the range of an area which extends some distance on opposite sides of the longitudinal axis of the machine, a guard 58, preferably of the endless belt type, as shown, is provided, the inner flight of the belt conforming to the arc of the periphery of the table or soil carrying element 1 between a pair of supporting rollers 59, which latter are journaled within the outer end portions of the diagonal U-shaped frame sections 23 (see Figures 1 and 4), the lower edge portion of the belt traveling in contact with the periphery of the element 1 but the major portion of the belt extending a considerable distance above the top face of the element to approximately the plane of the top edge of the annular guard flange 54 on the element. The arcuate flight of the belt 58 is supported midway between the supporting rollers 59 by an outer roller 60 similar to the rollers 59 and journaled just within the outer end of the longitudinal U-shaped frame section 4 and there being an inner roller 60a journaled within the frame section 4 and of smaller diameter and length to support the upper marginal portion of the arcuate flight of the belt in the region where it is supported by the outer roller 60. The outer flight of the belt 58 travels obliquely, as at 61, between the roller 60 and the respective rollers 59 (see Figure 1). By this provision, undue crowding and jamming of the material is prevented in its travel with the rotating table or soil carrying element 1 as the inner flight of the belt 58 travels with the periphery of said element 1.

A modified structure is illustrated in Figures 5, 6 and 7, wherein the main frame of the machine is substantially the same in structure as the longitudinal and transverse sections thereof which are illustrated in Figures 1 to 4, inclusive; that is to say, it includes front and rear substantially U-shaped sections 62 and 63, respectively, which are similar in general to the hereinbefore described sections 3 and 4, except that the leg members of said sections 62 and 63 are integrally joined at their inner ends and flattened at the joint, as at 64. There is a further difference in that the bar 65, which is the equivalent of the hereinbefore described bar 7, is continued with an integral horizontal extension 66 which is attached directly to the longitudinal side bar 29 of the frame, as at 67, the bars 29 and 65 carrying the scraper element 30 in the same manner that such element is mounted in the first herein described structure and the element 30 being cut away as at 33 the same as the hereinbefore described element 30. The transverse frame section 68 is substantially of the same form as the hereinbefore described section 8 except that both leg members thereof are integrally joined to the flattened connections between the leg members of the longitudinal frame sections 62 and 63, it being here also noted that the bar 65 is integrally secured at its inner end to the flattened connection between the upper leg members of the longitudinal sections 62 and 63. There is a further difference in the form of the frame section 68 in that its lower leg member 68a is straight throughout the major portion of its length and converges toward the upper leg of the section and its inner end portion is turned to be substantially parallel with the upper leg member and integrally attached to the flattened connec-

tion between the lower legs of the longitudinal frame sections 62 and 63, as at 69 (see Figure 6). In this modification, a ground wheel 36^a is substituted in place of the hereinbefore described wheel 36, said ground wheel 36^a being journaled on the convergent lower leg of the frame section 68 and being disposed more nearly vertical than the aforesaid wheel 36 but otherwise traveling on the ground and supporting and causing rotation to the annular table or soil carrying element 1^a in substantially the same manner as the aforesaid wheel 36. The wheel 36^a is not shiftable on the leg 68^a of the frame section 68.

In the modification illustrated in Figures 5, 6 and 7, the central annular deflecting flange or guard 54 is dispensed with and so is the endless belt guard 58, and in place thereof a rotary drum scraper element 70 is provided, said element 70 being in the form of a cylindrical cup having a flat bottom 71, or, obviously, in lieu of the flat bottom 71, its annular flange portion may be connected to a central hub by a plurality of radial members or spokes, because, in the function of said element 70, the annular flange portion thereof is the only part which acts to effect the discharge of the material from the table or soil carrying element 1^a, and in this connection it is preferable to provide radially projecting blades or wings 72 on the circumference of the annular flange of the element, by which provision the material carried on the table or soil carrying element 1^a is brought into engagement with said blades or wings 72 and causing rotation of the element 70.

The mounting of the rotary drum scraper 70 may be accomplished in any approved manner, but, as shown, it is provided at its center with an upwardly embossed portion 73 which is apertured for the reception of a headed axial stem 74 which is inserted upwardly through the aperture and being of a length so that it is extended through an aperture provided in a flattened portion 75 of the upper leg member of the frame section 63 intermediate the ends thereof (see Figure 6). The lower portion of the stem 74 is smooth surfaced, on which portion is sleeved rotatably a tubular member 76 which is provided at its lower end with an annularly flanged head 77 which supports the embossed hub portion of the drum 70, while the rest of the stem above the lower portion thereof on which the sleeve 76 is rotatably mounted is screw-threaded for the reception of opposed nut members 78 and 79, respectively, the nut 78 being located below and the nut 79 above the flattened portion 75 of the upper leg of the frame section 68, and opposed helical springs 80, of equal strength, being interposed between the nut members 78 and 79 and said flattened portion 75 of the frame section 63. The opposed spring elements 80 are of ample strength and adjustment to support the rotary drum scraper 70 normally in a neutral position where its weight is relieved from the top face of the table or soil carrying element 1^a, thereby minimizing wear and practically eliminating resistance to the travel of the annular working portion of the table or soil carrying element 1^a, the upper spring element 80 supporting the drum 70 and the lower spring resisting upward movement of the drum yet yielding to such movement should particles of the material of appreciable size work under the flat bottom 71 of the drum. However, if the drum be open-bottomed as when provided with radial members or spokes, as hereinbefore described, particles of

material entering beneath the drum will pass out through the openings between the radial members or spokes.

In the modification just hereinabove described, 5 the body frame of the machine may be effectively braced by providing diagonal stays 81 between the ends of the longitudinal frame sections 62 and 63 and the transverse section 68, as shown more clearly in Figure 5. The frame may be 10 further braced by providing a diagonal stay 82 which is attached at one end to the upper leg member of the front longitudinal frame section 62, as at 83, and at its opposite end to the flattened intermediate portion of the upper leg member of the transverse frame section 68, as at 84.

The structure may be further modified by substituting in place of the rotary scraper drum 70 an endless belt scraper element 85 which is 20 mounted at its opposite looped ends on rollers 86 and 87, respectively, the rear flight of the belt which travels across the rotating table or soil carrying element 1^a in the direction from the roller 86 to the roller 87 being deflected and supported by a roller 88 which is mounted on a special diagonal frame brace 89 intermediate the ends thereof (see Figure 8), thus giving angularity to this flight of the belt, but the other flight thereof traveling in a straight line between the rollers 86 and 87. The endless belt functions 25 in a manner similar to the rotary drum element 70 in that it is provided with lateral wings or blades 90 which are engaged by the material carried on the table or soil carrying element 1^a 30 causing the outer flight of the belt to travel from the roller 86 to the roller 87. In both modifications the tendency of both the drum 70 and the belt 85 is to rotate with the rotating annular table or soil carrying element 1^a thereunder in 35 the same direction that they are caused to travel by the engagement of the material therewith as the latter is carried on the element 1^a. In the modification illustrated in Figure 5 to 7, inclusive, the small front ground wheel 17 is eliminated and instead of providing a pair of rear ground 40 wheels 16 a single wheel 16^a is provided in line with the longitudinal axis of the machine (see Figures 5 and 7). So, too, inasmuch as the central upper and lower circular plates 5 and 6 are 45 eliminated, a bearing sleeve 11^a connecting the meeting ends of the upper and lower leg members of the respective frame sections is placed 50 on the strut member 11 (see Figures 6 and 7). Also, in this modification, the annular table or 55 soil carrying element 1^a has the outer end portions of radial members or spokes 14^a secured thereto and the inner ends of said members 14^a being attached integrally to the hub member 13^a 60 which is rotatable on the sleeve member 11^a.

While the structures illustrated in the accompanying drawings and herein described embody practical adaptations of the invention, it is obvious that considerable further modification and alteration may be made within the spirit and scope of the invention as defined in the appended claims. The invention, therefore, is not limited to the specific construction and arrangement shown.

What is claimed is:

1. In a rotary grader or terracer of the character described, a forwardly and laterally tilted annular table or soil carrying element rotatably mounted in a carriage frame of the machine, the lowermost peripheral portion of the table or soil carrying element being close to the ground and

forward and to one side of the axis of said element, a lateral soil deflector element mounted on the frame of the machine contiguous to the lowermost peripheral portion of the table or soil carrying element and being undercut to extend over and accommodate thereunder the adjacent marginal portion of said table or soil carrying element, the major lower portion of said deflector element riding upon the ground and deflecting the loosened soil ahead of it upon the rotating table or soil carrier, an annular upstanding guard flange located centrally of the rotating table or soil carrying element, a discharging deflector mounted on the frame of the machine at the side of the longitudinal axis thereof opposite to that on which the first mentioned deflector element is located, said discharging deflector extending diagonally across the top of the rotating table or soil carrying element with its inner end in slidable contact with said central annular guard flange at the rear thereof, and a guard element at the rear of said rotary table or soil carrying element extending contiguous to the periphery thereof between points on opposite sides of the longitudinal axis of the machine and conforming to the periphery of said rotating table or soil carrying element.

2. The structure as set forth in claim 1 and further including a ground wheel on the frame of the machine on the opposite side of the longitudinal axis thereof and diametrically opposite the first therein described deflector element, said ground wheel supporting the elevated adjacent marginal portion of the rotating table or soil carrying element whereby to impart rotation to said element during the travel of said wheel on the ground in the operation of the machine.

3. The structure as set forth in claim 1 and further including a ground wheel on the frame of the machine on the opposite side of the longitudinal axis thereof and diametrically opposite the first therein described deflector element, said ground wheel being shiftable longitudinally of its axis on the frame of the machine and radially with respect to the axis of the rotary table or soil carrying element so that, when said ground wheel is moved inwardly and positioned under the adjacent elevated marginal portion of the rotating table or soil carrying element the latter is thereby supported on the wheel and caused to rotate by the rotation of the wheel in its travel on the ground during the operation of the machine and when the wheel is shifted outwardly from under the table or soil carrying element the latter is then free of the support of the wheel and ceases to rotate other than by the contact of its lowermost peripheral portion with the ground, and manually operable means for shifting said ground wheel longitudinally of its axis and releasably holding it in the respective positions to which it is shifted.

4. The herein described grading and terracing machine, comprising an open main frame including rigidly connected longitudinal and transverse sections, said frame being provided with a trailing ground wheel or wheels for supporting its rear portion at an elevation above the ground and with the frame inclined forwardly with its front portion relatively close to the ground and also tilted transversely with the transverse portion of the frame at one side of the longitudinal axis thereof in close proximity to the ground and the diametrically opposite transverse portion being elevated, an annular table or soil carrying element rotatably mounted axially within

the frame of the machine whereby said element is tilted both longitudinally and transversely with its front marginal portion relatively close to the ground and its lowermost lateral marginal portion in approximate contact with the ground, a deflector element located at the longitudinal side of the main frame of the machine and contiguous to the lowermost marginal portion of the rotary table or soil carrying element and being undercut to receive thereunder the adjacent marginal portion of said table or soil carrying element, said deflector element riding with the major lowermost portion thereof in contact with the ground and acting to deflect soil loosened ahead of it onto the table or soil carrying element, and a ground wheel located on the main frame of the machine diametrically opposite said deflector element and supporting thereon the adjacent elevated marginal portion of the table or soil carrying element.

5. The structure as set forth in claim 4 and further including a central upstanding annular guard flange on the rotary table or soil carrying element, an arcuate discharging deflector mounted at one end on the main frame of the machine substantially diametrically opposite the first therein described deflector element and extending across the table or soil carrying element with its convex side disposed toward the rear of the machine and its opposite end portion resting in slidable contact with the rearmost portion of the peripheral face of said annular guard flange of the table or soil carrying element, and an endless belt guard element at the rear of the table or soil carrying element, the belt being supported at its looped ends upon rollers mounted in the adjacent frame portion of the machine on opposite sides of the longitudinal axis of the frame, the inner flight of the belt having its lower marginal portion in contact with the periphery of the table or soil carrying element throughout the extent thereof between the supporting rollers of the belt, the inner flight of the belt being supported on its outer side intermediate its end supporting rollers by an outer roller similar to the aforesaid supporting rollers, and an inner roller supporting the inner side of said inner flight of the belt in opposed relation to said outer intermediate roller, said outer intermediate roller also supporting the outer flight of the belt between it and said end supporting rollers of the belt.

6. In a rotary grader or terracer of the character described, a forwardly and laterally tilted annular table or soil carrying element mounted rotatably in a carriage frame of the machine, the lowermost marginal portion of the table or soil carrying element being that which is lateral and in close proximity to the ground, a lateral deflector element carried on the carriage frame of the machine adjacent to the lowermost peripheral portion of the annular table or soil carrying element, the major lower portion of said deflector riding on the ground and deflecting the loosened soil ahead of it onto the table or soil carrying element, and a traveler discharging deflector mounted on the carriage frame of the machine from the side of the longitudinal axis of the frame opposite to that on which the aforesaid lateral deflector is mounted and in diametrically opposite relation to said lateral deflector.

7. The structure as set forth in claim 6 and further more specifically describing the traveler discharging deflector as a rotary drum, the

periphery of which is provided with radial blades or wings.

8. The structure as set forth in claim 6 and further more specifically describing the traveler discharging deflector as a rotary drum yieldably supported axially thereof on the carriage frame of the machine with balanced spring tension to relieve the preponderance of the weight of the drum from the top face of the annular table or soil carrying element.

9. The structure as set forth in claim 6 and further more specifically describing the traveler discharging deflector as an endless belt disposed diagonally over the adjacent portion of the annular table or soil carrying element and provided with blades or wings on the outer surface thereof.

10. In a rotary grader or terracer of the character described, comprising a frame, a forwardly and laterally tilting annular soil carrying element rotatably mounted in the frame, the lowermost peripheral portion of the soil carrying element being close to the ground and forward and to one side of the axis of said element, a lateral soil deflecting element mounted on the frame beyond the soil carrying element and extending over a portion thereof, a discharge deflector mounted on the frame of the machine and extending over the soil carrying element at the

opposite side from the first mentioned lateral soil deflector element, and a guard element at the rear end of said rotary soil carrying element and extending contiguous to the periphery thereof between points on opposite sides of the longitudinal axis of the machine.

11. In a rotary grader or terracer of the character described, comprising a frame, a forwardly and laterally tilting annular soil carrying element rotatably mounted in the frame, the lowermost peripheral portion of the soil carrying element being close to the ground and forward and to one side of the axis of the element, a lateral soil deflecting element mounted on the frame beyond the soil carrying element and extending over a portion thereof, an annular upstanding guard flange located centrally of the rotating soil carrying element, a discharge deflector mounted on the frame opposite to that of the first mentioned deflector element and extending diagonally across the top of the rotating soil carrying element with its inner end in contact with the said central annular guard flange at the rear thereof, and a guard element at the rear of said rotary soil carrying element extending contiguous to the periphery thereof between points on opposite sides of the longitudinal axis of the machine.

ORRIN K. HOWE.
